UNITED STATES PATENT OFFICE.

JOSEPH SNYDER, OF WEST PITTSSTON, AND DATHAN MORSE, OF HUGHESTON,
PENNSYLVANIA.

COAL-CLEANER.

SPECIFICATION forming part of Letters Patent No. 281,735, dated July 24, 1883.

Application filed April 19, 1883. (No model.)

To all whom it may concern:

Be it known that we, JOSEPH SNYDER, of West Pittston, and DATHAN MORSE, of Hugheston, Luzerne county, Pennsylvania, and citizens 5 of the United States, have invented certain new and useful Improvements in Coal-Cleaners; and we do hereby declare the following to be a full, clear, and exact description of the invention, such as will enable others skilled in the art to which it appertains to make and use the same.

Our invention consists in a device for separating culm and slate from coal as it comes from the screen. The chief parts of our coal-cleaner, and to which our improvements relate, are an inclined chute, a cleaning-roll composed of alternate disks and flanges of peculiar construction, and a V-shaped comb or grate for preventing the roll from clogging.

20 In the drawings which illustrate our invention and make part of this specification, Figure 1 is a top view of our improved cleaner. Fig. 2 is an end view thereof. Fig. 3 is a section of the same in a plane indicated by the line x x , Fig. 1. Fig. 4 is an axial section of the cleaning-roll. Fig. 5 is a perspective view of the V-shaped comb or grate.

Like letters designate corresponding parts in all the figures.

30 The coal as it comes from the screen above our cleaner falls into the top of an inclined chute, A, mounted on a suitable frame. Near the upper end of the chute, and just below the place where the coal falls, is an opening 35 through which extends a segment of a revolving cleaning-roll, B, constructed in accordance with our invention. This roll is composed of disks C C and flanges D D, arranged alternately on the shaft E of the roll. The disks 40 C C have smooth unbroken peripheries, and are preferably beveled at their peripheries. Each disk may be beveled on one or both sides; or it may gradually increase in thickness from the periphery to the eye. The 45 plates or flanges D D are of greater diameter than the disks C C, and are constructed with teeth a a , of suitable shape, substantially as shown, on their peripheries. The spaces be-

tween the teeth a a on the flanges are preferably beveled in the same manner as the disks 50 C C, and the slanting edges of the teeth may also be beveled. The teeth, which at their points are as wide as the flanges are thick, are beveled gradually from their points down to their junction with the intermediate beveled 55 spaces. This construction of the teeth lessens the liability of breaking the teeth at the points. The shaft E, on which the disks and flanges are fixed, is of polygonal shape in section, and the eyes of the disks and flanges are of polygonal shape to correspond. This polygonal shape is superior to a circular shape of the shaft, as the disks and flanges are held much more firmly and steadily on the shaft; also, by making the flanges with a number of teeth 60 equal to one-half of the number of sides to the shaft, but one form of flange is necessary to be made to cause the teeth and spaces of adjacent flanges to alternate. Thus, if the shaft be of octagonal shape, as we have shown, 65 70 each flange would be formed with four teeth. Then by placing each flange on the shaft, one side to the right or left of the position of the preceding flange, the spaces and teeth of alternate flanges will alternate, as will be readily 75 understood.

To keep the disks and flanges at proper distances apart, we place between them washers or hubs b b. These hubs may be formed on one or both sides of either the disks or flanges, 80 or both; or they may be separate from either. If made separately, they should be made with eyes to fit the shaft. The hubs are of a thickness to keep the disks and flanges at a distance 85 apart suitable to permit the culm and slate to fall through between them. The outside disk at each end of the shaft is preferably made plain on the outer side, and the outside hubs, c c, are provided with screw-threads to correspond with screw-threads on the shaft, so that 90 the disks and flanges may be firmly and tightly pressed together, and be easily removed, if desired. It is only necessary to have one of the outside hubs removable, as the disks and flanges may all be put on at one end, and the hub 95 on the other end may be permanently fixed to

the shaft; or any suitable permanent stop may be provided. The peripheries of these outside hubs are made of suitable shape to receive a wrench—a hexagonal shape being a proper one—to permit of their being readily screwed or unscrewed. Their eyes are suitably formed to fit over the polygonal and screw portions of the shaft. The shaft E is extended at either end to receive a pulley, d, or other means for transmitting motion to the shaft.

At the opening in the bottom of the chute A, through which a segment of the roll B extends, each edge of the chute is made of notched or comb shape. The notches e e may be made in the chute itself; or they may be made in the plates attached to the bottom of the chute, depending on the material of which the chute is made. If the chute itself should be made of iron or steel, the notches might be cut in the chute; but if made of wood, the notches should be made in metal plates fixed to the chute. These notches are made of sufficient depth so that the spaces between them shall nearly reach to the disks C C, and so that the flanges D D may revolve in the notches. The spaces between the notches are of a width to correspond with the space between adjacent flanges, and the width of the notches depends upon the thickness of the flanges. The object of these notches is to prevent the coal from falling through the spaces between the flanges where they project beyond the disks. As the coal falls from the screen above, it descends down the chute and passes over the revolving roll B. The coal passes across the roll; but the culm and slate fall through between the disks and flanges. The beveled edges of the disks and flanges, together with the teeth, serve to turn the slate edgewise and cause it to fall more surely between said disks and flanges. Actual practice has demonstrated that fully three-fourths of the slate will be removed by a single passage over this roll. This cleaner is equally applicable to stove, chestnut, and other kinds of coal.

To prevent the spaces between the disks and flanges from clogging, we make use of a V-shaped comb or grate, F, such as is shown in Fig. 5. The bottom of this comb is of any suitable thickness, and the triangular teeth or bars f f are made of a length to suit the diameter of the roll B. They are long enough to reach almost to the peripheries of the hubs b b, and are of a thickness to suit the spaces between adjacent disks and flanges. The distance between the teeth f f depends upon the thickness of the disks and flanges. This V-shaped comb is placed directly under the shaft E, where it will not interfere with the falling culm or slate, and it is evident that it will force from between the disks and flanges any materials which may become clogged therewith.

All the various parts of our invention may be made of cast-iron or steel, or of other materials suitable to the functions of the undivided parts.

What we claim as our invention is—

1. A cleaning-roll composed of alternate smooth disks and toothed flanges separated by hubs or washers, substantially as and for the purpose herein specified. 70

2. A cleaning-roll composed of beveled disks and toothed flanges, substantially as and for the purpose herein specified.

3. A cleaning-roll composed of smooth disks 75 and beveled toothed flanges, the teeth of the flanges being beveled, as described, whereby they may be as wide at the points as the thickness of the flanges, substantially as and for the purpose herein specified. 80

4. A cleaning-roll composed of smooth beveled disks and beveled toothed flanges of different diameters, substantially as and for the purpose herein specified. 85

5. In a cleaning-roll, the combination of a 85 polygonal shaft and toothed flanges provided with polygonal eyes to fit on said shaft, the number of teeth on the flanges bearing a certain ratio to the number of sides on the shaft, substantially as and for the purpose herein 90 specified.

6. In a cleaning-roll, the combination of a polygonal shaft and alternate smooth disks and toothed flanges provided with polygonal eyes to fit on said shaft, the number of the teeth on 95 the flanges bearing a certain ratio to the number of the sides on the shaft, substantially as and for the purpose herein specified. 95

7. In a cleaning-roll, the combination of a polygonal shaft, alternate smooth disks and 100 beveled toothed flanges separated by hubs or washers, and formed with polygonal eyes to fit on said shaft, and a movable screw-threaded hub or hubs adapted to hold said disks and flanges tightly together on said shaft, substantially as and for the purpose herein specified. 105

8. The combination of the cleaning-roll, composed of alternate smooth disks and flanges of different diameters, and a notched chute, substantially as and for the purpose herein specified. 110

9. The combination of the cleaning-roll, composed of alternate smooth disks and toothed flanges of different diameters, and a notched 115 chute, substantially as and for the purpose herein specified.

10. A comb or grate composed of thin V-shaped teeth set parallel with one another, substantially as and for the purpose herein 120 specified.

11. The combination, with the cleaning-roll composed of alternate disks and flanges separated from each other, of a comb or grate composed of thin V-shaped teeth set parallel 125 with one another, substantially as and for the purpose herein specified.

12. A cleaning-roll composed of alternate disks and flanges separated by hubs or washers, in combination with a V-shaped comb or grate the teeth of which extend up between said disks and flanges, and reach nearly to said 130

hubs or washers, substantially as and for the purpose herein specified.

13. The combination of the cleaning-roll composed of alternate disks and flanges of different diameters, the notched chute, and the 5 **V**-shaped comb or grate, substantially as and for the purpose herein specified.

In testimony whereof we affix our signatures in presence of two witnesses.
